UNITED STATES PATENT OFFICE.

JOHN H. LAGREID AND OSCAR BECKLIN, OF SEATTLE, WASHINGTON.

WRENCH.

1,334,156.

Specification of Letters Patent. Patented Mar. 16, 1920.

Application filed November 25, 1918. Serial No. 264,012.

To all whom it may concern:

Be it known that we, JOHN H. LAGREID and OSCAR BECKLIN, subjects of the King of Norway and the King of Sweden, respectively, and residents of the city of Seattle, county of King, and State of Washington, have invented certain new and useful Improvements in Wrenches, of which the following is a specification.

10 Our invention relates to wrenches and consists of a wrench provided with means whereby it may be very quickly and very conveniently adjusted for different sizes.

15 The object of our wrench is to provide a strong and convenient wrench which may be quickly adjusted for different sizes and when adjusted may be securely locked, doing this all by simple, practical mechanisms.

20 The features of our invention which we consider novel, will be particularly pointed out in the claims. In the accompanying drawings we have shown our invention embodied in the type of construction which we now prefer to use and will describe such construction in detail.

25 Figure 1 is a side view of the wrench, with portions thereof in section and cut away in order to better show the details thereof.

Fig. 2 is a section taken upon the line 2—2
30 of Fig. 1.

Fig. 3 is an end view taken from the view point shown at 3—3 of Fig. 1.

Fig. 4 is a view of a portion of the back edge as indicated by the line 4—4 of Fig. 1.

35 The wrench, as herein shown, is provided with an inner jaw 10 and an outer jaw 20, which are toothed or roughened, so that it may grip any object upon which it is placed and thus may be used as a pipe wrench. It will be evident, however, that the principles of our invention may be used as well in a wrench which is not a pipe wrench, as in one which is a pipe wrench. Its scope is, therefore, not limited to application upon 40 pipe wrenches.

45 The inner jaw 10 is secured to or formed integral with the handle bar 1. The outer jaw 20 is secured to or formed integral with a shank 2, which lies alongside of the handle bar. The outer end of this shank and the outer jaw carried thereby, is secured against lateral movement by means of a retaining guide 3, which is carried by the outer end of the handle bar 1.

50 This guide is enough larger than the

shank 2 in one direction to permit a slight movement of the shank toward and from the handle bar. To normally hold this shank toward the handle bar we have shown a spring, as 30, in the form of a flat bar secured by one end to the inner surface of the guide. 60

The inner end of the shank 2 is pivoted, through the medium of a pin 21, to a sliding clip 4 which is mounted to slide freely upon the handle bar 1. The edge of the handle bar which is toward the shank 2 of the outer jaw, is provided with teeth which form a rack 11. 65

As indicated in Fig. 2, this rack is located rather toward one side of this edge of the handle bar. Preferably also the rack is made so that it is concave exteriorly, or as if it were a segmental portion of a long nut. 70

A locking bar 5 is journaled in the clip 4 75 and is provided with a segment 50 which is toothed so as to engage with the rack 11 and thereby lock the clip 4 against sliding movement on the handle bar 1. Preferably, the teeth on the segment 50, as well as the teeth in the rack 11, are formed as segments of screw or V-teeth. The recess 40 in the clip 4 is of a size to accommodate this segment lock and to permit its being thrown upward so as to disengage it from the rack 85 11. The pivot axis of this locking bar 5 extends in the same direction as the handle bar and the shank 2.

The axis of the locking bar 5 is preferably located toward one side of the central plane 90 of the handle end of the clip, and the rack 11 may be so located, so that when the locking segment 50 is turned up into the disengaged position, or that shown by dotted lines in Fig. 2, there will be room in the 95 clip to accommodate it.

The segment 50 extends radially somewhat beyond the pivot sections 51 of the locking bar, thus forming thrust shoulders 41, and the hollow in the clip 4, into which this locking bar is placed, is provided with complementary shoulders, which shoulders take the end thrust between the segment bar and the clip 4, due to the gripping action of the jaws upon a bar or pipe. 100

105 The end of the locking bar 5, which is toward the handle, projects from the clip and is so constructed that it may be readily engaged by the hand to turn it into either the locked or unlocked position. As herein 110

shown, it is provided with a lateral arm 52, and the side of this arm which is toward the clip 4 is brought to a dull edge, as shown at 53, this being engaged by a recess 60 formed in a flat spring 6 which is secured by one end to the clip 4.

By these means of locking, the bar 5 is held in the position in which the segment 50 is engaged with the rack 11. This furnishes 10 sufficient resistance to the movement of the locking block 50 to prevent disengagement, once a slight positive force is applied thereto.

The method of operating this wrench is evident. To adjust the jaws for different 15 sizes it is necessary to throw the locking block 50 into the position shown in dotted lines in Fig. 2, that is, with the lateral arm 52 extending to one side of the wrench. In this position the clip 4, and with it the outer 20 jaw 20, may be readily moved outward or inward, and when it has been brought down snug upon the pipe, rod, nut, or other object which it is to engage, the locking bar is turned into the position shown in Fig. 1 and 25 by full lines in Fig. 2. The teeth upon the locking segment 50 will thus engage the rack teeth 11 and securely hold the two jaws in their relative adjusted positions.

The slight movement of the outer jaw and 30 its shank toward and from the handle bar and inner jaw by locking upon the teeth 11, causes the wrench to more securely grip the pipe when pressure is applied to the handle to turn the pipe.

The locking bar 5 is secured after being 35 inserted in place by a small block 7, which completes the outer bearing.

What we claim as our invention is:

1. In a wrench, in combination, a handle bar having the inner jaw on one end thereof, 40 and having teeth on one edge forming a rack, an outer jaw, a clip slidable on the handle bar, the outer jaw being pivoted upon said clip, said clip having a recess opening toward said teeth, and a locking bar extending 45 lengthwise of the handle bar and journaled within the recess in said clip at one side of the median line of the clip and handle bar, and having a toothed segment adapted by turning to be engaged with and 50 disengaged from the said rack, said lock-bar having a pivot axis extending without said clip and carrying an operating arm upon its outer end.

2. In a wrench, in combination, a handle 55 bar having the inner jaw carried on one end thereof and having teeth on one edge forming a rack, a clip slidable on the handle bar, and having a recess opening toward the handle bar, an outer jaw having a shank pivoted 60 upon said clip, and a locking dog pivoted in said recess in the sliding clip upon an axis which extends parallel with the handle bar and offset laterally from a median plane of the handle bar and clip, said dog having a 65 toothed segment, and adapted by turning to engage and disengage said rack, the locking parts of said dog being entirely inclosed within said clip, said dog having a pivot axis extending without the clip and adapted to be 70 engaged to shift the dog.

JOHN H. LAGREID.
OSCAR BECKLIN.
